UNITED STATES PATENT OFFICE.

GEORGE B. KELLEY, OF ROCKFORD, ILLINOIS, ASSIGNOR TO THE ROCKFORD SILVER PLATE COMPANY, OF SAME PLACE.

BURNISHING-MACHINE.

SPECIFICATION forming part of Letters Patent No. 399,669, dated March 19, 1889.

Application filed November 19, 1888. Serial No. 291,194. (No model.)

To all whom it may concern:

Be it known that I, GEORGE B. KELLEY, residing at Rockford, in the county of Winnebago and State of Illinois, and a citizen of the United States, have invented a new and useful Improvement in Burnishing-Machines, of which the following is a specification, reference being had to the accompanying drawings, in which—

10 Figure 1 is a plan view, the drums being in section. Fig. 2 is a detail, being a side elevation of the clamp for holding the article to be burnished. Fig. 3 is a detail, being an end elevation of the clamp shown in Fig. 2. Fig. 15 4 is a detail, being a side elevation of the burnisher. Fig. 5 is a detail, being a longitudinal section through the burnisher. Fig. 6 is a detail, being a cross-section at line 6 6 of Fig. 4. Fig. 7 is a detail, being a plan view 20 of one of the tool-holders. Figs. 2, 3, 4, 5, 6, and 7 are enlarged.

This invention relates to burnishing-machines of the class shown and described in my patent, No. 356,842, dated February 1, 1887.

25 The leading object of this invention is to provide an improved burnisher, primarily designed to be used with the burnishing-machine shown and described in my said patent, but which will be found applicable to other forms 30 of burnishing-machines.

Another object is to provide an improved clamp for holding the articles to be burnished on the cylinder or drum.

I accomplish these objects as illustrated in 35 the drawings and hereinafter described. That which I claim as new will be pointed out in the claims.

In burnishing spoons, forks, and similar articles it is found that the varying surfaces of 40 such articles cause the burnishing-tools to press against the projecting or higher portions with more pressure than against concave or lower portions, thereby causing an uneven burnishing of the article. It is designed

45 to so construct a burnisher and to connect the tools at the opposite ends so that the tools will affect the action of each other and cause them to correspondingly follow the varying surfaces of spoons, forks, and similar articles 50 with equal pressure. The spoons, forks, or

other similar articles are to be burnished by placing them on the cylinders or drums in a reverse position—that is to say, while the bowl and upper surface of the spoon is being burnished by the tool at one end of the burnisher 55 the back of a corresponding spoon will be burnished by the tool at the opposite end of the burnisher, so that however varying the lines may be the movements of the burnishing-tools will be corresponding. 60

In the drawings, A A represent the rod which carries the burnishers.

B B are burnishers.

C are drums or cylinders, on the circumference of which the articles to be burnished are 65 clamped.

D D are clamps for clamping the articles to be burnished onto the cylinder or drum C.

E represents the articles to be burnished.

b is a tube which forms the body or main 70 portion of the burnisher B, and which is clamped by a set-screw to the reciprocating rod A, passing through a boss, a, on the tube b.

c c are two tool-holders—one in each end of the tube b—adapted to slide within the 75 tube b, as shown in Fig. 5.

d d are two burnishing-tools, one in each holder c.

e is a longitudinal slot or groove in each 80 tool-holder c.

f f are two pins secured near each end of the tube b, so as to project into the slot or groove e of the tool-holder c.

g is a spring, (see Fig. 5,) which is located within the tube b and presses the tool-holders 85 c outward.

h is a ring or collar on each tool-holder c, which limits the inward movement of the tool-holders by striking against the end of the tube b. 90

i are brackets which are secured to the edge of the cylinder or drum C, as shown in Fig. 1.

j is a stem or rod passing through the bracket i.

k is a head or handle on the outer end of 95 the stem j.

l is a coiled spring which surrounds the stem j and abuts against the bracket i and head k.

m is a head on the inner end of the stem j. 100

n is a recess in the head *m*, adapted to receive the end of a knife, spoon, or other similar article.

o is a projection on the under side of the head *m*.

p is a plane portion on the bracket *i*, on which the projection *o* slides, preventing the head *m* from turning.

q is a set-screw.

- 10 The operation is as follows: The knives, forks, spoons, or other articles to be burnished, *E*, are clamped on the cylinders or drums *C*, and are burnished by the burnishing-tools *d* of the burnishers *B*, which burnishers are reciprocated by the reciprocation of the rods *A*. The article *E* is clamped onto the cylinder or drum *C* by inserting its point in a recess near one edge of the drum *C*, (see Fig. 1,) and by pushing the stem *j* inward until 20 the handle of the article *E* is firmly held within the recess *n* of the head *m* and setting the set-screw *q*, which holds the stem *j* against retraction. The article is thus held against end movement by the set-screw *q*, and is held 25 against turning or twisting by the engagement of the projection *o* with the frame portion *p* of the bracket *i*. When it is desired to remove the article, the set-screw *q* is loosened and the spring *l* retracts the stem *j*, releasing 30 the article *E*. Each burnisher *B* is clamped to a reciprocating rod, *A*, at any desired point, according to the article to be burnished, by the set-screw in the boss *a*. The articles to be burnished—such as spoons and forks—are 35 placed on the drums or cylinders, so that the burnishing-tool *d* at one end of the burnisher *B* will burnish the front or concave portion of the article, while the tool *d* at the opposite end will burnish the corresponding back or 40 convex portion of a similar article, so that the movements of the tool-holders and tools will correspond—that is, while one is moving inward the other will move outward, so as to give the burnishing-tools an even pressure as 45 the lines of the articles vary. The rings or

collars *h* limit the inward movements of the tool-holders *c*, while the slots or grooves *e* and the pin *f* limit the outward movements and prevent the tool-holders *c* from becoming displaced. By this construction the face of one article and the back of another similar article can be burnished at the same time without giving any greater or additional pressure to projecting or higher parts, so that all parts of articles of irregular form can be properly 55 burnished.

Suitable apparatus for reciprocating the rods *A* is shown and described in my said former patent; but other suitable apparatus may be used.

What I claim as new, and desire to secure by Letters Patent, is—

1. The combination of the tool-holders *c c* and spring *g* with the tube *b*, substantially as specified.
2. The combination of the tool-holders *c c*, having the slots *e*, with the tube *b*, pins *f*, and spring *g*, substantially as specified.
3. The combination of the rod *A*, one or more tubes, *b*, having a boss, *a*, the tool-holders *c c*, and spring *g*, substantially as and for the purpose specified.
4. In a burnishing-machine, a cylinder or drum, *C*, in combination with a clamp, *D*, consisting of a bracket, *i*, stem *j*, head *k*, spring *l*, set-screw *q*, and head *m*, adapted to receive the article to be burnished, substantially as and for the purpose specified.
5. In a burnishing-machine, a cylinder or drum, *C*, in combination with a clamp, *D*, consisting of a bracket, *i*, stem *j*, set-screw *q*, head *m*, adapted to receive the article to be burnished, and provided with a projection, *o*, and the plane portion *p*, substantially as and for the purpose specified.

GEORGE B. KELLEY.
